UNITED STATES PATENT OFFICE

147,875

DESIGN FOR AN AIRPLANE

Joseph A. Shannon, Columbus, Ohio

Application May 14, 1946, Serial No. 129,689

Term of patent 14 years

(Cl. D71—1)

To all whom it may concern:

Be it known that Joseph A. Shannon, a citizen of the United States, residing at Columbus, in the county of Franklin and State of Ohio, has invented a new, original, and ornamental Design for an Airplane, of which the following is a specification, reference being had to the accompanying drawing, forming part thereof, wherein:

Figure 1 is a top plan view of an airplane showing my new design;

Figure 2 is a side elevational view thereof;

Figure 3 is a front elevational view thereof;

Figure 4 is a rear elevational view thereof;

Figure 5 is a side elevational view with doors and wheels retracted;

Figure 6 is a front elevational view with doors and wheels retracted; and

Figure 7 is a rear elevational view with doors and wheels retracted.

I claim:

The ornamental design for an airplane, as shown.

JOSEPH A. SHANNON.
